FOLDING BOX

Filed Nov. 14, 1927

UNITED STATES PATENT OFFICE

ARNOLD J. TANNER, OF NORTH HAVEN, CONNECTICUT

FOLDING BOX

Application filed November 14, 1927. Serial No. 233,919.

The present invention relates to folding boxes and the chief aim of the invention is to provide a simple, efficient and rigid box for containing a single article or a number of articles of a tapering shape, for example, shears or articles which are larger at one end than at the other. Heretofore, in common practice with folding boxes the box is made of a rectangular shape, and articles of a tapering shape are oppositely arranged so that the box is completely filled or if a space is left the same is filled by additional packing. According to the present invention, the box is so designed that the article or articles arranged in regular order completely fill the box and thereby the contents of the box are well packed without use of a filler. Furthermore, by means of the present invention considerable stock and storage space can be saved.

In the accompanying drawings an embodiment of the invention is shown as applied to a box which when set up is of a tapering shape but it will be understood the invention can be applied to other boxes of rhomboidal shape.

In the accompanying drawings, Figure 1 is a perspective view showing the complete box set up in a position for display;

Figure 2 is a bottom plan view showing the printed side of the blank of which the tray member of the improved box is constructed;

Figure 3 is a bottom plan view showing the printed side of the blank from which the cover or outer telescopic member of the improved box is constructed, and

Figure 4 is an elevation showing a separate member which is used as a display card.

Referring first to Figure 2 of the drawings, herein the blank is composed of a body member having extensions therefrom which are folded to form the set up tray member of the box. The various portions of the blank are designated by different reference numerals and the same numerals are applied

to the same parts when set up as shown in Figure 1. These parts include the main portion or body 1 of a tapering shape having side wings or portions 2 which are folded on the line *a*. The portions 2 carry the tongues 3 at each end and the extension 4 extends from the widest end of the portion 1 and the free end of extension 4 is folded upwardly on the line *b*. Portions 5 and 6, arranged to fold on lines *c*, are provided between portions 1 and 4 and at the other or narrow end of the portion 1, extension 7 is carried. The latter extension is arranged to fold on line *d* and the end of the extension 7 is preferably enlarged at 8.

Referring now to Figure 3, illustrating the blank of which the cover of the box is constructed. This blank is substantially the same as the other blank referred to, also having a main or body portion 9 with side portions 10 with tongues 11 extending from each end thereof. Extensions 12 and 13 extend respectively from the wide and narrow ends of the portion 9 and which extensions are arranged to fold on the dotted lines *e*. The extensions 12 and 13 carry respectively tongues 14 and 15. A slot 16 is cut in the main portion 9, the slot 17 is cut in one of the lower tongues 11 and open slots 18 are cut in the upper tongues 11 for the purpose hereinafter described.

In Figure 4 a separate display member or card 19 is shown and which member is of a tapering shape corresponding with the main portion 1 of the blank and which separate member 19 is arranged to fold at the bottom end on line *f*.

In the operation of assembling the box, the blank for the tray member is folded so that the portion 1 forms the bottom of the tray. The side portions 2 form the side walls of the box, portions 5 and 6 form one end of the tray and the portion 8 forms the other end of the tray. The portions 5-6 and 8 are folded over the tongues 3 and to facilitate

tate the folding of the smaller or narrow end the enlarged end 8 of the folded over portion bears against the side walls of the tray. The extension 4 is then folded over into the bottom of the tray to form a reenforced bottom and the end turned up from line *d* bears against the opposite folded end, and by these means the tray is rigidly held in its set up position.

The blank for the cover is folded in a similar way but to save stock, for one reason, the extension 12 does not extend the full length of the cover, but due to the tapered shape said extension fits closely into the tapered shape of the cover and is held against forward movement whereby said extension is retained in its folded position. The folded over portion 13 is held in its folded position by means of the engagement of the tongue 15 in the slot 17.

The extension 12 is so designed that it can be utilized as a support or bolster to hold the box in a more suitable angular position for display. The bolster is provided by folding the extension 12 under the box and engaging the tongue 14 in the slot 15. It will be understood when the box is displayed the tray member and the cover are reversed so that the cover will be at the bottom of the tray member and in this case it will be necessary to hold the cover member together at its widest end, so for this purpose the tongues 11 are provided with interlocking means such as the open slots 18.

The display card 19 is set up at the widest end of the box without any retaining means other than that obtained and due to the tapered shape of the folded end fitting within the tapered bottom of the tray member.

Certain other modifications may be made in carrying out the invention hereinbefore described, and it is to be understood that any modification coming fairly within the terms of the appended claim shall be covered thereby.

45 I claim—

A folding display and packing container comprising a tray member of a rhomboidal or tapering angular shape, said tray being composed of a single sheet blank obliquely scored longitudinally to divide said blank into a main portion and side portions, said main and side portions forming respectively the bottom and sides of said tray member, said blank being transversely scored to provide parallel portions, said side portions having folding tongues extending therefrom, said parallel portions being adapted to fold over said tongues to form the ends of said tray member, said main portion of the blank having an extension therefrom of a shape corresponding with that of said main portion and being adapted to fold into said tray member to provide a double bottom therefor and also means whereby the ends of the tray member

are retained in position, a cover for said tray member similar in construction and shape to said tray member with the addition of means for holding said tongues together and means for rendering said extension from said main portion operative as a supporting easel for 70 the container.

Signed at New Haven, county of New Haven, State of Connecticut, this 12th day of November, 1927.

ARNOLD J. TANNER.
